UNITED STATES PATENT OFFICE.

LEWIS C. LEWIS, OF COLUMBUS, OHIO, ASSIGNOR TO THE MONARCH MANUFACTURING COMPANY, OF COLUMBUS, OHIO, A CORPORATION OF OHIO.

WATER-MOTOR.

No. 870,112.

Specification of Letters Patent.

Patented Nov. 5, 1907.

Application filed October 1, 1906. Serial No. 336,866.

To all whom it may concern:

Be it known that I, LEWIS C. LEWIS, a citizen of the United States, residing at Columbus, in the county of Franklin and State of Ohio, have invented certain 5 new and useful Improvements in Water-Motors, of which the following is a specification.

My invention relates to water motors.

In many instances, motors of this character are used to actuate pumps. In some sections of the country, 10 the natural water supply is very hard and it is customary to provide water lifts in residences, said water lifts being actuated by the city water pressure and being utilized to elevate soft water from a cistern to the upper floors of the residence in which the lift is 15 located. Since these lifts are used in residences, it is important that they should work with as little noise as possible and the present invention is designed to provide a motor for a water lift which will be absolutely noiseless in operation, the shifting of the valves 20 which control the water supply to the cylinder, being accomplished by water pressure and said valves being water cushioned at each end of their stroke.

Further objects and advantages of the invention will be set forth in the detailed description which now follows.

In the accompanying drawings: Figure 1 is a vertical section of a motor constructed in accordance with the invention, illustrating the main piston at one end of its stroke and illustrating the valves at one of their 30 limits of movement, Fig. 2 is a like view illustrating the piston at the opposite end of its stroke and the valves at their opposite limit of movement, Fig. 3 is a transverse vertical section upon line $z-z$ of Fig. 2 looking in the direction indicated by the arrow, Fig. 4 is a 35 side elevation of the valve chambers illustrating the arrangement of the ports hereinafter described, and, Fig. 5 is a view looking from the opposite side of said valve chambers, illustrating the arrangement of exhaust ports hereinafter described.

40 Like reference numerals designate corresponding parts in all of the figures of the drawing.

Referring to the drawings, the numeral 5 designates the cylinder of the water motor. Mounted in this cylinder is the usual piston 6, said cylinder being secured to a piston rod 7. This piston rod may in turn be secured to any driven member, such as a pump, not shown. A stuffing box 8 of the usual and well known construction, prevents leakage about the piston rod 7. The head 9 which closes the right hand 45 end of the cylinder 5, in Fig. 1, is provided with an extension 10 which has a port 11 formed therethrough. A by-pass 12 leads from the port 11 to a port 13, said port being formed in a cap 14 which is secured to the end of a casting 15. This casting 15 has valve chambers 16 and 17 formed therein, the outer ends of these

chambers being closed by a web 18 and their inner ends being closed by plugs 19. One of these plugs 19 carries a stuffing box 20 through which a rod 21 passes. Mounted upon the rod 21 are collars 22 and 23, the collar 23 lying inside of the hollow piston rod 7 and 60 said piston rod being provided with a shoulder 24 which serves a purpose hereinafter described. Slidably disposed within the valve chamber 17 is a valve 25 having two heads 26 and 27, said valve being secured to the end of the rod 21. Slidably disposed 65 within the valve chamber 16 is a valve comprising heads 28, 29, 30 and 31, said heads being constructed in the usual manner by clamping leather disks between metallic washers. The detail construction of these heads forms no part of the present invention. 70

The sides of the casting 15 are closed by plates 32 and 33, the space which lies between the plate 32 and the walls of the valve chambers 16 and 17, forms an exhaust chamber 34 (see Figs. 3 and 5). Exhaust ports 36 and 37 are formed in the walls of the chamber 75 16 and establish communication between said chamber and the exhaust chamber 34, it being understood that the exhaust pipe 35 (see Fig. 3) communicates with this chamber, said pipe being carried by the plate 32. As is best illustrated in Figs. 3 and 4, the space 80 which lies between the plate 33 and the walls of the valve chambers 16 and 17 is divided into a plurality of chambers 38, 39, 40, 41 and 42 by suitable ribs 43 which are integral with the casting 15.

Attention being still directed to Fig. 4, it will be 85 seen that a port 44 establishes communication between the chamber 38 and the port 13 of the cap 14. It will also be seen that a like port 45 establishes communication between the chamber 40 and the interior of the cylinder 5. Ports 46 establish communication between the chamber 38 and the interior of the valve chamber 16. Ports 47 establish communication between the chamber 42 and the interior of the valve chamber 16. Ports 48 establish communication between the chamber 40 and the interior of the valve 90 chamber 16. A port 49 establishes communication between the chamber 39 and the interior of the valve chamber 17. A port 50 establishes communication between the chamber 42 and the interior of the valve chamber 17. A port 51 establishes communication 100 between the valve chamber 41 and the interior of the valve chamber 17. Ports 52 and 53 establish communication between the chambers 41 and 39 and the interior of the valve chamber 16 at the opposite ends thereof. Exhaust ports 54 lead from the extreme 105 ends of the valve chamber 17 to the exhaust chamber 34. An inlet pipe 55 which is carried by the plate 33 is adapted to conduct water from any suitable source of water supply to the chamber 42.

The operation of the device is as follows: Water be- 110

ing supplied to the chamber 42, we will assume that the parts are in the position illustrated in Fig. 1. At this time the piston 6 has reached its limit of movement toward the right and the shoulder 24 by striking 5 the collar 23, has moved the rod 21 and shoved the valve 25 to the right. At this time the port 50 is in communication with the port 51 through the chamber 17, the water passing through the port 50 into said chamber between the heads 26 and 27 of the valve 25.

10 The water then passes out of the port 51 into the chamber 41, thence through the port 52 to the interior of the chamber 16 where it acts upon the head 31 to shift the valve of which said head forms a part, to the left in Fig. 1, or to the position illustrated in said figure.

15 When this is done, the ports 46 are in communication with the ports 47 through the chamber 16, the water entering from the chamber 42 through the ports 47 to the interior of said chamber 16 between the heads 29 and 30, passing thence through the ports 46 to the 20 chamber 38, thence through the port 44, port 13, by-pass 12 and port 11 to the right hand end of the cylinder 5, where it acts to move the piston toward the left in Fig. 1. When this piston reaches its limit of movement toward the left in Fig. 1, the end of the piston 25 rod strikes the collar 22 and shifts the valve rod 21 and consequently the valve 25 to the position illustrated in Fig. 2. During this movement of the piston toward the left in Fig. 1, the exhaust of the water contained in the cylinder upon the left side of the piston, is accomplished as follows: The water to be exhausted 30 passes through the port 45 to the chamber 40, thence through the ports 48 and between the heads 30 and 31 to the interior of the valve chamber 16. From this chamber, the water passes through the exhaust ports 36 to the exhaust chamber 34 and thence through the exhaust pipe 35 to the waste pipe. When the valve 35 is in the position illustrated in Fig. 2, communication is established between the ports 49 and 50. The water then enters from the chamber 42 through the 40 port 50 to the valve chamber 17 and between the heads 26 and 27. It passes from said chamber through the port 49 which has now been uncovered by the head 27 and brought into communication with the port 50, into the chamber 39. It passes from the chamber 39 45 through the port 53 to the chamber 16 where it acts upon the head 28 to shift said head and the valve of which said head forms a part, to the position illustrated in Fig. 2. This movement of this valve, establishes communication between the ports 47 and 48, the water entering from the chamber 42 through the ports 47 and between the heads 29 and 30. The water then passes 50 from the chamber 16 out of the ports 48 to the chamber 40, thence through the port 45 to the cylinder 5 where it drives the piston toward the right. During the 55 movement of the piston toward the right in Fig. 2, the water contained in the cylinder 5 upon the right hand side of said piston, is driven out through the port 11, by-pass 12, port 13, port 44, chamber 38, ports 46 to the valve chamber 16, and from said valve chamber 60 through the exhaust ports 37 to the exhaust chamber 34 and thence through the exhaust pipe 35 to the waste.

It is apparent that it is necessary to provide some means for the exhausting or the escapement of the 65 water which enters the chamber 16 to actuate the valve,

and this is accomplished in the following manner. After the valve has been shifted to the position illustrated in Fig. 1, when water enters at the left of the chamber 16 to shift said valve to the position illustrated in Fig. 2, the water contained in the chamber 16 at the 70 right hand end of the valve, is forced through the port 52 to the chamber 41 passing thence through the port 51 to the interior of the chamber 17 and thence through the exhaust port 54 to the exhaust chamber. With the valve in the position illustrated in Fig. 2, when 75 water enters at the right hand end of said valve to shift it to the left, the water contained at the left hand end of said valve is forced through the port 53 to the chamber 39, thence through the port 49 to the chamber 17 passing from said chamber to the other port 54 through 80 the exhaust chamber and thence to the waste.

From the foregoing description, it will be seen that means are herein provided for supplying water to one side of the piston until said piston reaches the limit of its stroke and for then supplying water to the opposite side of said piston to return said piston. Means are also provided for exhausting the water from each side of the piston. Means are provided for shifting the valves which control the flow of this water by water pressure and means are also provided for the exhaust of the water which has been used in shifting the valves.

By referring to Fig. 4 of the drawing, it will be seen that the exhaust ports 52 and 53 are so located that the valve leathers of the valves 28 and 31 will cut off the 95 flow of fluid through said ports before the valve reaches its end of travel. Consequently a small amount of water will be caught between the ends of the valve and the ends of the valve chamber to cushion the valve, said valve being thereby prevented from bumping against the ends of the valve chamber.

From the foregoing description, it will be seen that simple and efficient means are herein provided for accomplishing the objects of the invention, but while the elements shown and described are well adapted 105 to serve the purposes for which they are intended, it is to be understood that the invention is not limited to the precise construction set forth, but includes within its purview such changes as may be made within the scope of the appended claims.

What I claim, is:

1. A water motor comprising two centrally disposed valve chambers 16 and 17, an exhaust chamber located upon one side of the centrally disposed valve chambers, an exhaust pipe leading from said exhaust chamber, a central chamber 42 located upon the opposite side of the valve chambers, chambers 38, 39, 40 and 41 located upon the same side of the valve chambers as the chamber 42, ports establishing communication between all of said chambers and the valve chambers, ports establishing communication between both of the valve chambers and the exhaust chamber, a main cylinder, a port establishing communication between the chamber 40 and one end of the cylinder, a port 44 establishing communication between the chamber 38 and the opposite end of the cylinder, a primary valve located in one of said valve chambers, a secondary valve located in the other of said valve chambers, means for causing the piston to move the primary valve at each end of its stroke, said primary valve controlling the flow of fluid to the secondary valve, and said secondary valve controlling the flow of fluid to the cylinder.

2. A water motor, comprising two centrally disposed valve chambers 16 and 17, an exhaust chamber located

- upon one side of the centrally disposed valve chambers, a central chamber 42 located upon the opposite side of the valve chambers, chambers 38, 39, 40 and 41 located upon the same side of the valve chambers as the chamber 42, 5 there being ports establishing communication between all of said chambers and the valve chambers and there being ports establishing communication between both of the valve chambers and the exhaust chamber, a main cylinder, there being a port establishing communication between the chamber 40 and one end of the cylinder, a chamber 13 located at one end of the valve chambers, there being a port 44 which establishes communication between the chamber 13 and chamber 38 and there being a by-pass 35 establishing communication between chamber 13 and the opposite end of the cylinder, a primary valve located in one of said valve chambers, a secondary valve located in the other of said valve chambers, a rod which projects through the cylinder head into the cylinder and is rigidly connected to the primary valve, a hollow piston rod in which the end of said rod is disposed to travel, and means for causing the piston to shift said rod at each end of its stroke. 40
- 10 4. A valve casing for water motors, comprising two centrally disposed valve chambers 16 and 17, an exhaust chamber located upon one side of the centrally disposed valve chambers, a central chamber 42 located upon the opposite side of the valve chambers, chambers 38, 39, 40 and 41 located upon the same side of the valve chambers as the chamber 42, there being ports establishing communication between all 50 of said chambers and the valve chamber, ports establishing communication between both of the valve chambers and the exhaust chamber, a port establishing communication between the chamber 40 and one end of the cylinder of a water motor, a port 44 establishing communication between the chamber 38 and the opposite end of the cylinder, and valves mounted in said valve chamber. 55
- 15 5. In testimony whereof I affix my signature in presence of two witnesses. 60
- 20
- 25
- 30
- 35
- 40
- 45
- 50
- 55
- 60
3. A water motor, comprising two centrally disposed valve chambers 16 and 17, an exhaust chamber located upon one side of the centrally disposed valve chambers, a central chamber 42 located upon the opposite side of the valve chambers, chambers 38, 39, 40 and 41 located upon the same side of the valve chambers as the chamber 42, there being ports establishing communication between all of said chambers and the valve chambers and there being ports establishing communication between both of the valve chambers and the exhaust chamber, a main cylinder, there being a port establishing communication between the chamber 40 and one end of the cylinder, a chamber 13
